BY *John W. Wiedersheim*

ATTORNEY.

UNITED STATES PATENT OFFICE.

ADAM BENDER, OF PHILADELPHIA, PENNSYLVANIA.

DESIGN FOR AN EMERY-WHEEL DRESSER.

SPECIFICATION forming part of Design No. 28,323, dated May 29, 1894.

Application filed April 18, 1893. Serial No. 470,889. Term of patent 14 years.

To all whom it may concern:

Be it known that I, ADAM BENDER, a citizen of the United States, residing in the city and county of Philadelphia, State of Pennsylvania, have invented and produced a new and original Design for a Dresser for Emery-Wheels, of which the following is a specification, reference being had to the accompanying drawings, forming part thereof.

Figure 1 represents a side elevation of a dresser for an emery wheel embodying my design. Fig. 2 represents a view taken from the periphery thereof.

The leading feature of my design for a dresser for emery wheels is the oblique ar-

rangement of teeth across the periphery thereof.

In the drawings, A designates a dresser for emery wheels, the same consisting of a disk having teeth B on the periphery thereof, said teeth extending in oblique rows across said periphery.

What I claim is—

The design for an emery wheel dresser, as shown and described.

ADAM BENDER.
